UNITED STATES PATENT OFFICE.

NEVILLE HUNSMERGER, OF ALDAN, PENNSYLVANIA, ASSIGNOR TO SAMUEL STERNBERGER, OF PHILADELPHIA, PENNSYLVANIA.

SAFETY-PIN.

1,135,692.

Specification of Letters Patent. Patented Apr. 13, 1915.

Application filed September 12, 1914. Serial No. 861,352.

To all whom it may concern:

Be it known that I, NEVILLE HUNSMERGER, a citizen of the United States, residing at Aldan, county of Delaware, State of Pennsylvania, have invented a new and useful 5 Safety-Pin, of which the following is a specification.

My invention consists of a safety pin which is provided with means adapted to 10 prevent accidental displacement of the point of the pin proper from the shield of the device, as will be hereinafter set forth.

The invention is satisfactorily illustrated in the accompanying drawing, but the important instrumentalities thereof may be varied, and so it is to be understood that the invention is not limited to the specific details shown and described.

Figure 1 represents a side elevation of a 20 safety pin embodying my invention. Fig. 2 represents a partial side elevation and partial longitudinal section thereof. Fig. 3 represents an end elevation of the shield on an enlarged scale. Fig. 4 represents a transverse section on line $x-x$, Fig. 2. Fig. 5 represents a plan view of a portion of the pin proper on an enlarged scale. Fig. 6 represents a longitudinal section of a portion 25 on line $y-y$, Fig. 3.

Similar numerals of reference indicate 30 corresponding parts in the figures.

Referring to the drawings:—1 designates the pin proper of a safety pin, 2 the point portion thereof, 3 the back member thereof, 35 and 4 the coil which is intermediate of the member 3 and the pin proper 1 and imparts resiliency to the latter.

5 designates the shield, whose lower portion in the position shown in the drawings 40 is connected firmly with the adjacent terminal of the back member 3 and whose upper portion is adapted to receive the point portion of the pin proper 1.

On the opposite sides of the point portion 45 of the pin proper are the grooves 6, which form the reduced neck 7, these several features thus far described being well known.

The shield 5 is composed of a piece of light metal bent on itself so as to embrace 50 tightly the member 3 and provide opposite thereto, the chamber 8 to receive the point portion of the pin proper 1, which features are well known.

The inner ends of the side walls of the 55 channel 8 are inturned toward each other,

forming the lips 9, whose inner edges are separated from each other, forming the channel 10, through which the neck 7 is adapted to pass, said channel being tapering in what may be called upward direction, 60 said lips being somewhat resilient so that they may separate laterally and then close toward each other.

In what may be termed the tops of the lips 9 is the recess 11, which is open below 65 so as to be in communication with the adjacent end of the channel 10, the same being adapted to receive the point portion of the pin 1 about the grooves 6 and neck 7. The upper terminals of the walls of the channel 10, where they join the lower terminal of the divided wall of the recess 11 form the shoulders 12, which project toward each other, the walls of the recess 11 gradually blending with the inner face of the bend 13 of the 70 back of said guard and joining the same, said bend and walls forming said recess of circular form to conform to the circular form of the portion of the point part of the pin around said neck 7, as most plainly 75 shown in Fig. 3.

The operation is as follows:—The point portion of the pin proper is introduced into the shield when the walls of the grooves 6 contact with the inclined tapering edges of 80 the opposite lips 9, thus spreading apart the latter by a wedging action. The point portion rises in the shield to full extent and enters the recess 11, when the base of the neck 7, which owing to the grooves 6 is of less 85 width than the adjacent portions of the pin, clears the shoulders 12 and is just above the shoulders 12. Then the lips 9 are no longer controlled by said neck, whereby they spring 90 together, and the shoulders close under said neck with a snap and engage with the same, said neck thus being seated on said shoulders and so interlocked with the latter as it is clamped tightly by said shoulders from below, while the upper curved portion of the 100 pin around said neck is pressed solidly against the bend 13, so that the pin is held comparatively without play on the guard and clamped immovable therein, and so is prevented from displacement downwardly, 105 the device thus remaining in position without liability to move therefrom under ordinary circumstances.

When the pin is to be opened, the pin proper is pressed in a direction toward the 110

back member 3, when the neck rides on the shoulders 12, forcing apart the lips 9, allowing the neck to pass through the channel 10 to the lowermost end of the latter when the 5 pin proper is moved laterally and so clears the shield, the effect of which is evident.

I am aware that it is not new to form the shield of a safety pin with inturned lips and shoulders on the latter near the beginning 10 of the same, whereby said shoulders are removed from the pin point when the latter occupies the shield, and said point is not seated on said shoulders.

I am aware also that it is not new to form 15 inturned projections on the sides of the shield by swaging the metal of said sides, the same forming recesses in the outer faces of said sides which are objectionable in appearance and liable to fracture the metal of 20 said sides, while being necessarily small on the inner faces of said sides have not sufficient holding power for the pin point, but in my construction, the sides of the shield are left in the normal unbroken condition of 25 the metal of the same, the lips 9 are on the extreme inner ends of said sides, the shoul-

ders 12 are close to the back bend 13 of the shield so as to support the pin point thereon in its full position against said bend, and said point fully fills the circular recess 11 30 formed by the shoulders 12 and said back bend preventing any lost motion of the pin point in said recess, wherefore

What I claim as new and desire to secure by Letters Patent, is:—

In a safety pin, a pin proper having in the side of its point portion a groove and a neck, and a pin point shield bent upon itself to form a back and side walls and having on the inner ends of its side walls inwardly extending lips entirely separated from each other and tapered from their outer ends inwardly, said lips having inwardly extended shoulders adjacent to the back of the shield whereby said neck is seated on the shoulders 45 of said end lips while being held tightly against the back of the shield and so interlocked by said shoulders and back.

NEVILLE HUNSMERGER.
